UNITED STATES PATENT OFFICE.

FRANK L. ROBINSON, OF OMAHA, NEBRASKA, ASSIGNOR OF ONE-HALF TO ROBERT H. GARRETT, OF OMAHA, NEBRASKA.

ELECTRICAL ADVERTISING DEVICE.

Application filed September 30, 1926. Serial No. 138,770.

This invention relates to an electrical advertising device, and has for its object, broadly, to provide a device to be placed in railway stations, hotels or other like places for use of the public generally, and particularly for the use of strangers or visitors in a city, for giving information of prominent business houses, hospitals, parks or other places of interest, the device to be of such construction that it may be operated conveniently by any person without the aid of others.

The invention includes a frame preferably disposed in an upright position of sufficient size to display a map of the city and to also display the names of business houses and institutions, together with public places of interest, and certain electrical devices which may be illuminated by the visitor or operator for visibly pointing out the locations of the particular places, and thereby giving to the operator the information desired.

A particular object of the invention is to provide a pivotally mounted wing for the frame, as a matter of convenience when adjusting the illuminants and renewing the bulbs for the electric lamps employed, also to provide a convenient mounting for the lamps. With the foregoing objects in view and others to be mentioned hereinafter, the invention presents a novel and useful construction, combination and arrangement of parts as described herein and claimed, and as illustrated in the accompanying drawing, it being understood that changes in form, size, proportion of parts and minor details may be made as found to be of advantage, said changes being within the scope of the invention as claimed.

In the drawing, which illustrates one embodiment of the invention, Fig. 1 is a front view of the device illustrating parts of a map and, in dotted lines showing the location of certain lamps ready to be illuminated. Fig. 2 is a transverse section through the frame, showing location of the lamps. Fig. 3 is a rear view of the device, the door of the frame or casing being removed to show electrical devices carried by the pivotally mounted wing. Fig. 4 is a transverse section through the frame or casing showing the door and the wing when swung outwardly. Fig. 5 is a front view of the wing. Fig. 6 is a view illustrating electrical circuits. Fig. 7 is an enlarged detail showing

an incandescent lamp mounted upon the front side of the wing, the lamp socket-holder and sleeve surrounding the lamp being in section.

Referring now to the drawings for a more particular description, numeral 10 indicates a frame or casing preferably provided at its front with a transparent plate 11 as best shown in Figs. 2 and 4 of the drawings. Numeral 12 indicates a plurality of electrical switch-control members or push-buttons which are mounted on a vertical strip 13, outwardly of the transparent plate.

At the inner side of the glass plate and preferably secured thereto is a map 14, and adjacent to members 12 are horizontally arranged spaces 15 bearing the names of business establishments and other names of interest, as indicated at 16 located in the city represented by the map, and since streets and blocks, respectively indicated at 17 and 18, are shown on the map, the approximate location of said establishments may be pointed out to a visitor or operator of the device, as will be explained.

While I have shown a casing or frame to be rectangular in side elevation, this is not important, and the size or proportions of the casing may be greater or less, depending on the population or size of the city, and, of course the number of prominent business establishments, and other places of interest, such as parks, hospitals, hotels, banks and the like, may be greater or less, and the operation will be the same.

In order that the objects may be attained as first mentioned, certain electrical parts are provided to be explained. Numeral 19 indicates an operating-wing which is disposed rearwardly of and adjacent to the map 14, said wing being hinged to the frame as indicated at 20 said wing being provided with a plurality of lamps 21 and a master-lamp 22, as best shown in Fig. 3 of the drawings, and it will be understood that this wing may swing outwardly approximately a quarter of a circle to dispose the lamps in an upright position, and may be swung inwardly to the position shown in Fig. 2 of said drawings.

This wing may be constructed of wood or any other material having a limited degree of electrical conductivity. It is provided with a metallic sheet 23 at that side thereof next to the map 14 to operate as an

electrical conductor, and in order that the bulbs α may be suitably housed and protected from injury and that they will be conveniently accessible for removal or adjustment,

- 5 I provide certain features consisting, in part, of horizontal holder-strips 24 provided with flanges 25 for receiving the flanges 26 of the lamp socket-holders 27. By referring to Fig. 7 of the drawings it will be seen that 10 these members 27 have a lesser length than the bulbs α of the lamps. Numerals 28 indicate sleeves which are slidably mounted in the holders 27, and when the wing is swung inwardly of the casing, the ends of the 15 sleeves 28 will engage the map and, since the map is transparent or practically so, the lamps will illuminate parts of said map. The sleeves are of such proportion that they 20 snugly engage the map when the wing has been swung to a vertical position so that no parts of the map will be illuminated except the area defined by the open ends of the sleeves.

I provide a plurality of normally open 25 electrical circuits energized by any suitable means, as by an electrical battery 29. Numeral 30 indicates an electrical conductor leading from one pole of the electrical battery to the master-lamp 22 and said metallic 30 sheet 23, and an electrical conductor 31 is in communication with the opposite pole of the electrical battery and with a plurality of electrical contact-pieces 32 for certain electrical switches 33.

35 Numerals 34 indicate electrical conductors, each being in communication with a lamp 21 and with a contact-piece 35 of an electric switch 33, and it will be understood that the electrical switches may be actuated by an 40 operator by use of members 12, and if one of said members 12 is moved or pushed inwardly of the strip 13, as usual in the use of "push-buttons" one of the switches 33 will be actuated to cause illumination of the master-lamp 22 and one of the lamps 21.

The parts are so arranged that when the wing 19 is swung inwardly, the sleeves 28 for the lamps 21 will register with those parts of the map which correspond to the 50 names 16 and said members 12, and simultaneously with said illumination the master-lamp will be illuminated.

Since the master-lamp indicates the place or location of the device, and since it will 55 be illuminated in conjunction with each lamp 21 an operator unacquainted with locations in a city may be visibly informed as to the distance, approximately, as well as direction of the particular place he wishes 60 to visit without making inquiry of others.

Among some of the advantages to be derived by use of the invention, it may be stated that it provides gratuitous and correct

information to visitors or strangers in a city and operates to advantage as an advertising medium, and will be found useful in public places, such as railway stations and hotels.

Since the incandescent lamps will require occasional adjustments they are mounted on a wing which may have swinging movements, and since it may be necessary to remove a lamp occasionally or to provide an additional lamp for pointing out a new location on a map, the holder-strips 24 are a great advantage, since the lamps by this construction may be securely held by the flanges thereof, and may be disposed adjacent to any part of the map.

I claim as my invention,—

1. In an electrical advertising device, the combination with a frame provided at one of its sides with a map and names referring to said map and a plurality of switch-control members, of a wing pivotally mounted on the frame at the side thereof opposite to said map, a plurality of holder-strips provided with flanges and secured to said wing, a plurality of lamp socket-holders having flanges engaging the flanges of said holder-strips, a plurality of lamps each disposed in a socket-holder, a plurality of sleeves each surrounding a lamp and removably mounted in a socket-holder, a master lamp, a plurality of normally open electrical circuits each including a source of electrical energy, an electrical switch, a lamp, and said master lamp, said wing being movable to cause engagement of the sleeves with said map, and each switch-control member being movable for closing an electrical circuit.

2. In an electrical advertising device, the combination with a supporting frame having one of its sides provided with a map and bearing names, a wing mounted on that side of the frame opposite to said map, a plurality of holder-strips disposed approximately parallel with reference to each other and secured to said wing, a plurality of socket-holders engaging the flanges of the holder-strips, incandescent lamps in the socket-holders, sleeves each surrounding a lamp and removably mounted in the socket-holders, a master lamp, a plurality of electrical circuits each including a source of electrical energy, an electrical switch, said master lamp and an incandescent lamp, and a plurality of electrical switch-control members each being movable for closing an electrical circuit, said wing being arranged to permit swinging movements thereof to cause engagement of the sleeves with said map.

In testimony whereof, I have affixed my signature.

FRANK L. ROBINSON.
